PRESSURE RECORDER SEAL

Hugh B. Webster, Oakland, Calif., assignor to
 Standard Oil Company of California, San
 Francisco, Calif., a corporation of Delaware

Application December 23, 1939, Serial No. 310,803

1 Claim. (Cl. 73—300)

This invention relates to fluid pressure recorders of the type that are used in deep wells, such as oil wells, and particularly refers to an improved means for separating the sealing liquid used in contact with the working parts of the pressure responsive means from the fluids in the well or other space in which the pressure measurement is to be taken.

In the drilling and operation of deep oil wells it is desirable and sometimes necessary to make recorded measurements of fluid pressure in the well bore at varying flow rates and with various arrangements of packers, formation testers, tubing valves, chokes and other equipment used in this art. Typical instruments used for such purposes are described in Patents No. 1,837,222 to Kannenstine, No. 1,955,855 to Marx, and No. 2,078,623 to Wilde. The depths at which these devices are used and the fluid pressures to be measured thereby have increased during the past few years to a point where it becomes increasingly difficult to keep the well fluids, under pressures up to 7,500 pounds per square inch, isolated from the pressure transmitting liquids that are usually employed in contact with the delicate moving parts in the pressure responsive mechanisms. When it is understood that the conditions of use of certain of these recorders limit their outer diameter to not over 1 1/4 inches, the necessity for keeping oil, water, sand, gas, and the like out of the internal parts will be appreciated. Various expedients such as screens, flexible metallic bellows, elastic diaphragms or sacks, and the like have been used, but these are necessarily so small that they are not always effective, and, in addition, if they should fail by bursting, the interior of the apparatus unavoidably becomes filled with the well fluid, which renders it inoperative and usually unfit for further use.

This invention comprehends broadly an improved means for separating the pressure transmitting liquid usually used in a recorder of this type, from the well fluids whose pressure is to be measured, said means comprising a rigid member sliding freely in a carefully machined bore, and preferably with flow control means permitting flow outwardly from the pressure transmitting liquid to the well fluids, in case of expansion of the former by temperature rise or other causes, but preventing flow in the opposite direction. In this example, the machined bore is open at one end to the well fluid and at the other to the pressure liquid, and the solid member comprises a free piston in the bore with

a check valve in the piston body for the fluid restraining function just mentioned.

It is an object of this invention to provide an improved means for sealing the interior parts of a deep well pressure recorder from abrasive or corrosive fluids in the well bore.

Another object is to provide a sealing means of this character all of whose parts are made of rigid material that is not susceptible to fatigue, corrosion or attack by high temperature or the well fluids.

Another object is to provide a sealing means which will provide a greater displacement volume for pressure transmitting liquid than the expedients heretofore employed for this purpose.

Another object is to provide a sealing means that will permit escape of the pressure transmitting liquid from its system into the well fluids in case of undue expansion of said liquid due to temperature rise or other causes.

Another object is to provide a sealing means that will act as a safety check valve in case of failure of other sealing means in the interior of certain types of pressure recorders, to prevent flooding the clockwork and other internal parts by the pressure transmitting fluid or the well fluids.

Another object is to provide a sealing means of this character that is not only simple and economical to fabricate but also may readily be adapted to existing pressure recorders, to improve their operating characteristics and insure their internal parts against damage.

These and other objects and advantages will be further apparent from the following description and from the accompanying drawing, which forms a part of this specification and illustrates a preferred embodiment of the invention as applied to a deep well pressure recorder.

40 In the drawing, Figure 1 is a longitudinal sectional view, to an enlarged scale, of a preferred embodiment of a seal for a pressure recorder.

Figure 2 is a longitudinal sectional view of the seal of Figure 1 in place in a recorder of the Standard or Marx type.

Referring to Figure 2, which illustrates the general arrangement, the pressure recorder there shown comprises a fluid tight casing or housing 10 provided at its upper end with an attachment 11 for the conventional wire line 12, and a fitting 13 for the engagement of an overshot fishing tool in case of breakage of the line 12. A clockwork 14 in housing 10 is adapted to rotate a shaft 15 and chart holder 16 at a desired rate,

for example, one revolution in eight hours, the chart 17 being retained inside the holder.

In this example the pressure responsive means comprises a piston 18 axially movable in bore 19 through fluid sealing means or packing 20, and restrained by spring 21 in the desired manner. The upper end of piston 18 is provided with a stylus or marking means 22 which makes a trace or record on chart 17 as the latter rotates. Chamber 23 into which piston 18 projects and which contains spring 21 is filled with a pressure transmitting liquid 24 which may be a refined oil, such as castor oil, and which not only protects the parts just named from the well fluids but also serves to lubricate and assist in the sealing functions of packing 20.

A passage 25 leads from the bottom of first chamber 23 into the sealing means to which this application is particularly directed, and one example of which is shown in detail in Figure 1. Desirably housing 10 is provided with a downwardly depending hollow, cup-like extension member 26 connected thereto by threads 27. An opening 28 in a wall of extension 26 permits communication of well fluid pressure from outside the device to a second chamber 29 inside of member 26. A tube 30 is secured to housing 10 by threads 31 and is open at its upper end to passage 25 leading from the pressure fluid chamber 23 of the recording mechanism described above. The bore 32 of tube 30 is accurately machined to receive a similarly finished rigid piston member 33 which is movable through the bore and is closely fitted thereto.

The lower end of bore 32 is preferably provided with an apertured or ported plug 34, the latter serving to retain piston 33 in the bore and, in this arrangement also adapted to hold a filter medium 35, which may be retained in plug 34 by a threaded apertured closure member 36. The apertures in plug 34 and member 36 permit well fluid or other fluid or liquid from chamber 29 to pass through filter medium 35 and thence into the bore 32 of tube 30 below piston 33. Under some circumstances such filtering of the well fluid may not be necessary, but where sand or mud is present it is usually advantageous.

Desirably some means are provided to permit the pressure liquid 24 to flow outwardly from chamber 23 or bore 32 into the space surrounding the instrument or into chamber 29, said last named chamber also including the space in bore 32 outside of piston 33, in case of excessive expansion of the liquid due to temperature changes or other causes. In this example such means are located in the piston 33, and take the form of a longitudinal bore 37 in which is mounted a ball valve 38 urged toward its seat by spring 39. This permits outward flow of pressure liquid but prevents inward flow of well fluid.

To place the instrument in operation the chart 17 is placed in holder 16, the device is inverted and cup member 26 and plug 34 are removed. Filling plug 40, which is provided in body 10 to communicate with first chamber 23, is removed and the chamber 23 and bore 32 are pumped full of a suitable sealing liquid 24, such as castor oil, until piston 33 is forced out of bore 32 and the liquid emerging is free from entrained gas or air bubbles. Filling plug 40 is replaced and piston 33 is forced into bore 32, the valved passage 37 permitting escape of the liquid displaced. Plug 34 and cup member 26 are replaced, the instrument returned to its upright position, and, if desired, that portion of the second chamber

29 in cup member 26 is also filled through port 28 with the same sealing liquid as is used in the instrument.

In operation, an increase in pressure on the fluid in which the device is immersed is transmitted hydraulically through port 28, chamber 29 and the passages in member 36, against the lower face of piston 33, forcing the latter upwardly into bore 32 and imparting the same pressure on sealing liquid 24, which, in turn, forces the movable member, in this example axial piston 18, upwardly in bore 19 against the resistance of spring 21 into the chamber for the recording or exhibiting element in housing 10. The quantity of sealing liquid 24 forced upwardly from bore 32 replaces or fills the space in chamber 23 formerly occupied by that portion of the axial piston which has been displaced by the pressure increase. Piston 33, which acts to separate the liquid 24 in bore 32 from whatever fluid may be below that piston, serves effectively to seal the pressure transmitting liquid from the well fluids which may enter chamber 29 through pressure port 28. If the pressure responsive piston packing 20 should fail, pressure transmitting liquid 24 would be forced upwardly into the chart housing, but only to an amount that would be present above piston 33 in bore 32, as that piston would stop at the top of bore 32 and prevent complete filling of the chart and clock chambers.

Thus it will be appreciated that improved sealing means has been provided for pressure recorders of this character, these means generally comprising a bore or passage open at one end to the pressure transmitting liquid in the device and open at the other end to the source of fluid pressure to be measured, with a closely fitted rigid member slidably in said bore. Desirably, but not necessarily, flow control means are provided selectively to by-pass said member, and in addition, filter means may be included to protect the bore and member from abrasive materials in the fluid whose pressure is to be determined. Obviously the improvement is not only applicable to the axial piston type of pressure recorder here described but to the Bourdon tube type of Kannenstine, whose tube, if it should burst, would flood the working parts with well fluid, as well as those other types in which a pressure transmitting liquid may be used and in which it is desirable that the said liquid be separated from the well fluids.

Although a specific example has been shown and described, it is apparent that many changes and modifications could be made in it without departing from the invention, and it is to be understood that all such that fall within the scope of the appended claim are embraced thereby.

I claim:

In a pressure recorder provided with a first chamber, a movable member at one end of said chamber, said member being connected to an exhibiting element, a spring for opposing movement of said member, said first chamber being filled with a sealing liquid for transmitting fluid pressure changes to said member to move the latter, means adjacent said member at one end of said chamber for filling it with said sealing liquid, means forming a cylindrical passage leading from the opposite end of said first chamber to a second chamber communicating with the fluid whose pressure is to be measured, an unattached rigid cylindrical member filling the

bore of said passage, said member being freely movable therein and effective to separate said sealing liquid from fluid entering said passage from said second chamber, and a check valve in said cylindrical member to permit liquid to flow from said first chamber into said second chamber during the filling of said first chamber with sealing liquid and at such other times that the pressure in said first chamber exceeds

5 that in said second chamber, said check valve being effective to prevent fluid flow in the opposite direction, said movable member, first chamber, cylindrical passage and check valve being aligned to promote evacuation of air or fixed gases from the sealing liquid in said first chamber and said passage during said filling operation.

HUGH B. WEBSTER.
